(**) Term: **15 Years**

(57) **CLAIM**

(21) Appl. No.: **29/571,278**

I claim the ornamental design for a wheelchair brake attachment bracket, as shown and described.

(22) Filed: **Jul. 15, 2016**

DESCRIPTION

(51) **LOC (10) Cl.** 12-12

FIG. 1 is a top perspective view of a wheelchair brake

(52) **U.S. Cl.**

attachment bracket showing my new design;

USPC **D12/133**

FIG. 2 is a side elevation view thereof;

(58) **Field of Classification Search**

FIG. 3 is an end elevation view thereof;

USPC D12/128-133

FIG. 4 is an opposite end elevation view thereof;

CPC A61G 5/00-5/14; B62B 7/00-7/04; B62B

9/00-9/28; A61H 3/00; A61H 3/04

FIG. 5 is a top view thereof;

See application file for complete search history.

FIG. 6 is a bottom view thereof;

(56) **References Cited**

FIG. 7 is an opposite side elevation view thereof;
